TELEPHONE APPARATUS

Florentino G. Troisi, Pittsburgh, Pa.

Application August 29, 1935, Serial No. 38,469

4 Claims. (Cl. 179—119)

The present invention relates to a telephone instrument intended to function in a system as transmitter or receiver, independently of external current sources, and constitutes a continuation in part of my application Serial Number 713,023 filed on February 26, 1934.

Due to inherent defects and general inefficiency, instruments of the so-called batteryless type heretofore constructed, have failed to meet with 10 commercial success. In most cases the diaphragms of such instruments have been strained beyond desirable limits in an attempt to obtain maximum amplitudes of vibration and a minimum weight of the moving system. In attempts 15 to balance the mechanical system, balance of the magnetic circuit has been overlooked with a resulting imperfection of sound transmission.

Units conforming to the present construction find application for any installations wherein local 20 telephone systems are used, such as for ships, apartment houses, hotels, offices, mines, factories, etc., as well as for submarine salvage as disclosed in the parent application already referred to.

In use as a transmitter, the unit of the present 25 invention derives its actuating current from the sound vibrations impressed upon the diaphragm, obviating the need for batteries or other external current sources. As a receiver, the unit converts the incoming electrical currents to sound waves 30 which are reproduced by the diaphragm. While especially intended for use without external current sources, the interposition of a battery or other current source in the circuit is also contemplated.

Faithful reproduction is obtained throughout 35 the audio frequency range with units of the present construction, by virtue of the proportions of the various masses and arrangements resorted to. Undue damping is avoided, and injury to the 40 parts is prevented.

The armature of the electromagnetic circuit is supported in a truly balanced condition, and measures are taken to preserve a balance of the magnetic circuit as a whole.

Sound vibrations impressed upon the diaphragm 45 of transmitter or receiver alike, represent more nearly the mean values, whereby distortion is overcome and the diaphragm is subjected to smaller strains than in known structures.

It is with the object of overcoming the faults of 50 prior constructions and of attaining the ends already outlined, that the present invention is proposed, the details of which will be understood from the following description in conjunction 55 with the accompanying drawings.

Fig. 1 is a partially exploded view of the telephone unit;

Fig. 2 is a detail of portions of the magnetic system, partially broken away.

Fig. 3 is a sectional elevation taken along line 5 3—3 of Fig. 1 with the parts in assembled relation;

Fig. 4 is a portion of the section along line 4—4 of Fig. 1 with the parts assembled;

Fig. 5 is a plan view of the diaphragm;

Fig. 6 is a plan view of the partially assembled 10 unit; and

Fig. 7 is an elevation showing one manner in which a pair of the units may be combined as a 15 set.

A diaphragm 18 is sandwiched between a spacing ring 11, and an annular boss 12 which is integral with and protrudes from a perforated cover plate 13, whereby an air chamber is defined between the diaphragm and cover plate. The spacing ring 11 has a bearing upon a plate 14 which serves as a support for the various elements. The base plate and cover plate are provided with registering openings 15 and 16 respectively, for the 20 reception of assembly screws. Another set of openings provided in the cover plate are intended to receive screws for attachment to a housing, not shown, for enclosing the working parts in watertight condition.

Secured to the base plate 14 by bolts 17, is the 25 assembly for effecting the induced currents in response to the voice or other sound frequencies impressed upon the diaphragm. This assembly comprises a permanent horseshoe magnet 18, pole pieces 19, an armature 20, an armature housing 21, a winding 22 properly insulated from the metallic structure, and means for holding the various elements in assembled relation and properly spaced. A pin 23 couples the diaphragm assembly 30 to the armature, to which elements its respective ends are positively connected, though adjustably, by solder or the like.

The bolts 17 have their heads countersunk in the base plate, their shanks extending through the same with a forced fit in order to maintain them in rigid, spaced relation. The spacing of these bolts is such, that the ends of the horseshoe magnet 18 are nicely received therebetween and frictionally held thereby. Counterbored 35 openings formed near the opposite ends of the magnet, receive the screws 24 which threadedly engage the pole-pieces 19 to fasten the same to the poles of the magnet. Each of the pole-pieces is preferably formed from a flat sheet of magnetic material, which is cut to a substantially T- 40 45 50 55 60 65 70 75 80 85 90 95

shape, the horizontal bar of the T tending to converge at its extremities by virtue of a slight taper on its lower edge. In assembled relation, these pole-pieces each have a vertical portion contiguous to and coextensive with the poles of the horseshoe magnet. One end of each of these vertical portions (in Fig. 3 the upper end of the left hand pole-piece and the lower end of the right hand pole-piece) joins a horizontally extending portion which is substantially coplanar with one of the planes of the horseshoe magnet. The tips of the pole-pieces are formed by folding inwardly towards the axial plane of the permanent magnet, a pair of wings which constituted the horizontal bar of the original T. These wings or tips of the respective pole-pieces extend towards one another, but are maintained in a predetermined spaced relation by a series of lugs 25 extending from the armature housing.

20 A light weight armature 20 of magnetic material, and substantially rectangular in plan, has a short perforated integral lug 26 extending centrally from one side thereof. Parallel to the side bearing the lug 26, on a line passing through the center of gravity of the armature, a pair of openings are formed, symmetrical with respect to said center of gravity, through which the ends of a supporting pin 27 are passed. The pin is preferably a length of resilient wire having its ends bent at 90° to their base, forming a pair of parallel arms. The base of the pin is permanently attached to the armature, as by soldering or the like, indicated at 28.

The ends of the pin 27 are received in openings 35 formed in the upper surface of a one-piece armature housing 21 which is of rigid, light nonmagnetic material, preferably metal. The armature is centered in its housing, whereupon the pin ends are riveted and affixed to the housing by soldering or the like. The housing comprises a top surface, a pair of side walls perpendicular thereto, opposed base portions spaced from one another and parallel to the top surface, and carefully calibrated lugs 25 projecting from both ends 45 of both side walls, making four in all. The upper and lower edges of all of these lugs 25 lie in two parallel planes, for the purpose of spacing the pole pieces 19. The base of the housing, being discontinuous, prevents to a large extent, the effects of eddy currents.

50 Bridging the gap between the base portions of the armature housing, there is provided an insulating block 29, which in conjunction with its insulating wrapping 30, spaces the spool flanges 31 of insulating material, which are provided with elongated slots for the reception of the armature housing. Thus, except for its lugs 25, the armature housing serves as a core for the magnet winding 22 which is formed upon the 55 wrapping 30 and between the flanges 31. These elements are held in assembled relation by bending the four lugs 25 outwardly along their line of junction with the housing proper. After the predetermined number of turns of suitable gauge wire have been applied on the spool, an insulating covering 32 is wrapped about the coil so formed.

A clamping bar 33 of non-magnetic material is provided with openings for the reception of the 70 threaded ends of the bolts 11, for clamping the assembly to the base plate upon application of the nuts 34. The bar is provided with a pair of locating pins 35, preferably pressed from the material of the bar itself, which pins are received 75 in a pair of cooperating openings in the upper

surface of the magnet. Also, the bar is preferably bowed downwardly at its central portion so as to resiliently bear against the horizontal portion of the upper pole-piece 36. The lower pole-piece is also given a definite bearing surface 5 against the base plate by designing the latter in the manner shown in Fig. 6. The central aperture of the base plate is formed of two concentric semi-circles of different radii. Thus the smaller semi-circle 37 leaves sufficient material to support 10 the pole-piece without unduly damping the diaphragm, while the larger semi-circle 38 provides a sufficiently large passage for air within the instrument so as not to interfere with its sensitivity and operation.

15 As shown in Fig. 4, the armature is preferably terminated in the planes of the pole-piece surfaces so as to be cut by substantially the total flux emanating therefrom. To prevent breakage through fatigue, the armature lug 26 is made 20 as short as possible, and to allow for the solder 25 or the like applied thereto for holding the pin 23, the rear surfaces of the pole-pieces are provided with grooves 40. A further and more important function of these grooves, is the balance 25 of the magnetic system which is achieved thereby. The projecting lug 26 tends to decrease the reluctance of the gap at the rear of the pole-pieces, which factor is compensated by reducing the area of the pole faces at this point. Consequently, the torque applied at the opposite sides 30 of the fulcrum provided by the pin 27 will be equalized and likelihood of distortion diminished.

35 After the diaphragm 10 is clamped into position, the pin 23 is inserted through the opening in the lug 26, and with the armature assigned to its final neutral position with respect to the opposed pole tips, the pin is fixed to the lug. Should the diaphragm subsequently become bent, or should there be need of adjustment for another reason, the pin may be readjusted with 40 respect to the armature lug and a new joint formed.

The ends of the winding 22 are brought out to a suitable terminal block 41, from which they are 45 connected to their respective conductors for completing a circuit with one or more similar units.

The diaphragm 10 is preferably a thin disk of 50 resilient flexible material, such as duralumin, highly responsive to voice frequencies, which in the form shown, has been impressed with a series of concentric corrugations, the spacing and depth of which in general, increase as their diameters decrease.

55 Whereas it is usual practice in devices of this type to solder or otherwise connect the center of the diaphragm directly to the pin which transmits the movements to or from the armature, more reliable and generally better reproduction 60 has been obtained in this construction by transmitting movements between diaphragm proper and the pin through an intermediate, substantially rigid member which is supported at a plurality of points on the diaphragm. To prevent 65 undue damping of the diaphragm, this member is attached at the peak of a corrugation, being otherwise out of contact with the diaphragm.

This connecting member 42 which is preferably of light yet rigid construction, has a body 70 portion of substantial cone shape, terminating at its base in a rigidifying bead 43, extending from which, there are a plurality of short stiff lugs 44 which are perforated for the reception 75 of rivets 45 for attachment to the diaphragm 75

at the peak of a corrugation 46. After the parts have been riveted together, solder is preferably applied to the rivet heads to assure an air-tight and substantial joint, after which a coating of 5 a waterproof and plastic material such as a wax is applied over the solder.

As shown, three lugs connect the member 42 with the diaphragm, this number having been chosen as a balance between light weight and 10 rigidity, both of which factors are important. Whether the movements are transmitted from the diaphragm to the armature while the unit serves as a transmitter, or from the armature to the diaphragm when in use as a receiver, a 15 more nearly perfect reproduction is effected than with a pin connected at a single point to the center of the diaphragm. The number of such lugs may be varied without departing from the spirit of the invention.

20 The air chamber between the diaphragm and the diaphragm cover is designed with respect to the moving system, that is, the diaphragm, its pin and the armature, so that when a plurality of the units are connected in a circuit, the circuit will be substantially uniformly responsive 25 to frequencies throughout the audible range. The resonance of a unit used as a receiver will be different than when it is used as a transmitter, due to a change of its effective air chamber, and the number of different resonant frequencies of the system will be increased, tending 30 to render uniform the output of the system over the entire audible range.

As appears in Fig. 3, the length of the pole 35 tips is necessarily slightly greater than the length of the armature housing for the lugs 25 to perform their function of spacing these pole tips uniformly.

These telephone units operate as transmitter 40 or receiver interchangeably, and due to their construction, operate efficiently under the high pressure conditions to which they are frequently subjected as in under water salvage operations. When used as a transmitter, the vibrations of 45 the diaphragm set up by the voice, are imparted to the balanced armature through the pin 23. The movements of the armature in the field of the permanent magnet, vary the reluctance of the magnetic circuits with a frequency proportional to that of the sound waves producing these 50 movements. Accordingly, proportional currents will be induced in the winding, which currents will be carried to similar units serving for the instant as receivers. When current flows in the receiver winding, magnetic flux will be produced 55 to oppose or reinforce that of the permanent

magnet, depending upon the direction of the current. Thus the armature will become unbalanced and be caused to vibrate about its fulcrum, which vibration will be transmitted to the receiver diaphragm and be emitted as sound waves. 5

Fig. 7 depicts a pair of such telephone units assembled as a hand set, having a single casing for the units, the cable being led into the casing through a watertight stuffing box.

Although the construction of the telephone 10 units especially adapts them to use in connection with submarine salvage apparatus, they have been highly successful in other uses and their application is not to be restricted beyond the scope of the appended claims. 15

I claim:

1. A telephone unit comprising a permanent magnet carrying a pair of detachable pole pieces, an electromagnet embraced by said pole pieces, said electromagnet comprising a spool having 20 separate flanges and a discontinuous one-piece sheet metal armature housing having elements holding said spool in assembled relation and projecting between said pole-pieces and in contact therewith for limiting the positions of the latter. 25

2. A telephone unit comprising a permanent magnet carrying a pair of pole-pieces, an electromagnet embraced by said pole-pieces, said electromagnet comprising an armature and a one-piece sheet metal housing therefor, a spool 30 composed of a plurality of elements formed about said housing, said housing carrying lugs engaging and holding the spool in assembled relation and contacting said pole-pieces for spacing the latter. 35

3. A telephone unit comprising a base plate carrying a pair of spaced bolts, a horseshoe magnet carried by said base plate having its legs in frictional engagement with said bolts, pole-pieces carried by said magnet having surfaces coplanar 40 with those of the magnet and a clamping bar receiving said bolts engaging coplanar surfaces of said magnet and said pole-pieces for clamping the same to said base plate.

4. A telephone unit comprising a horseshoe magnet having a pair of oppositely directed pole-pieces rigidly attached thereto, said pole-pieces having surfaces coplanar with those of the magnet, a clamping bar engaging the upper surfaces 45 of a pole-piece and the magnet and having positioning pins received by apertures in the magnet, a base plate engaging the lower surfaces of a pole-piece and the magnet, and means for associating said clamping bar with said base plate 50

55 FIORENTINO G. TROISI.
